UNITED STATES PATENT OFFICE

90,673

DESIGN FOR AN APRON

Russell J. Meeks, Spokane, Wash.

Application September 21, 1932
Serial No. 45,011

Term of patent 3½ years

To all whom it may concern:

Be it known that I, RUSSELL J. MEEKS, a citizen of the United States, residing at Spokane, in the county of Spokane and State of Washington, have invented a new, original, and ornamental Design for Aprons, of which the following is a specification, reference being had to the accompanying drawing, forming a part thereof.

Figure 1 is a front view of the apron.

Figure 2 is a side view of the apron, and
Figure 3 is a view showing the apron from the
rear.

I claim:—
The ornamental design for an apron substantially as shown.

RUSSELL J. MEEKS.
